UNITED STATES PATENT OFFICE

FRANCIS JOHN BLATZ, OF NEW YORK, N. Y.

GOLF BAG

Application filed May 2, 1931. Serial No. 534,675.

This invention relates to golf bags and has for an object to provide an improved construction for use with golf sticks or clubs of half length or full length but separable centrally.

Another object of the invention is to provide a golf bag wherein a number of clubs of half length proportion and a single handle may be carried, the structure being such that when the bag is being carried or supported from the upper part, the handle and club sections will be out of sight, while they will project above the upper end of the bag when the bag has been placed on the ground.

Another object, more specifically, is to provide a golf bag wherein a telescoping lower portion is provided whereby the effective length of the bag will vary so that the golf sticks will project above the top of the bag when in one position and may fall short of the top of the bag when in a second position.

In the accompanying drawing—

Figure 1 is a perspective view of a golf bag disclosing an embodiment of the invention.

Figure 2 is a longitudinal vertical sectional view through the golf bag shown in Figure 1.

Figure 3 is a view similar to Figure 2 but showing the bag in position when resting on the ground with the telescoping parts slid together.

Figure 4 is a sectional view through Figure 3 approximately on line 4—4.

Figure 5 is a side view of a golf club section and handle, the handle being shown separate but in operative position in dot-and-dash lines.

Referring to the accompanying drawing by numerals, 1 indicates a golf bag as a whole, and 2 a golf stick as a whole, said golf stick comprising a club section 3 and a handle section 4 removably connected with a section 3. The golf club section 3 is preferably approximately half the length of the usual golf club and the handle 4 is also of half the length of the usual golf club handle, said handle being connected with the club section 3 by suitable fastening structure 5. By reason of using the half length structure on section 3 a number of different clubs may be carried in the bag 1 and a single handle 4 as illustrated in dot-and-dash lines in Figures 2 and 3.

When any particular club is to be used, it

is removed from the bag and a handle 4 connected therewith. If it is desired to change the clubs, a club section is removed and placed in the golf bag, while the club section of another club is removed and fastened to the handle so that when the handle is in place, the golf club structure will be of the usual length now in common use.

Referring more particularly to the golf bag, it will be noted that the same is provided with a body 6 which may be made of any material but preferably of some stiff material, as for instance fibre. This body is associated with a telescoping section 7 of metal, bakelite, fibre and the like. The section 7 is provided with a bottom 8 of metal or other desired material, said bottom being rigidly connected to the side walls of the section 7 and provided with a flange and grooved structure 9 for receiving the cover or lid 10, when the same is not in use. Articulated members 11 are provided at a number of points around the telescoping section 7, there being four shown in Figure 4, but it will be evident that more or even less could be used without departing from the spirit of the invention. Each of these articulated members is formed with a bar 12 pivotally mounted at 13 on bracket 14 and extending slightly past bracket 15 connected with a ring 16 rigidly secured in any desired manner to body 6. A link 17 is pivotally connected at 18 to bracket 15 and at 19 to the sleeve 20, which sleeve is pinned or otherwise rigidly secured to the bar 12.

The pivotal pins 15 and 18 are preferably in vertical alignment while the pivotal pin 19 is positioned inwardly toward the section 7 whereby the downward pressure of the body 6 and associated parts will normally hold the bar 11 pressing against the link 17, even when the parts are resting on the ground as shown in Figures 1 and 2. When it is desired to leave the bag resting on the ground, one or more of the arms 11 are grasped and pulled outwardly past dead center and then the parts will move to the position shown in Figure 3 and remain in that position until the bag has been raised. As soon as the bag has been raised, the parts will again assume the position shown in Figure 2. This arrangement provides bracing feet for preventing the bag from upsetting while permitting the person carrying the bag to merely grasp the handle 21 and raise the bag whereupon

the parts will quickly assume their normal position shown in Figure 2. The lid 10 is provided with an ornamental bead 22 to agree with the flange 23 so that when the top is forced beneath the flange 23, a complete ornamental bead will be presented as shown in Figure 1, and the top will be held properly in place. Preferably, the parts are so proportioned that the top 10 will be held in place by friction, either in the position shown in Figure 2 or in the position shown in Figure 3.

In order to provide proper separation for the different clubs and also the handle, an apertured plate 24 is provided having a desired number of apertures 25 through which the small parts of the clubs are passed and also through which the handle 4 is passed as illustrated in Figures 2 and 3. A stiff rod or tube 26 is connected at its upper end with the plate 24 and at its lower end with the bottom 8, said connection being by riveting, welding, or other suitable means. The plate 24 is provided with a notch or cut-out portion 27 for accommodating the pocket 28, said pocket being used for balls. This pocket may be flexible or rigid as preferred. It will be noted that when the lid 10 is in a closed position all of the clubs and the balls are protected from the weather and also are out of sight.

I claim:

1. A golf bag including a body open at both ends, a cover for one end of said body, a telescoping section fitting in the other end of the body, a solid bottom for said telescoping section, and a plurality of hinged members connecting said bottom with said body whereby the telescoping section may slide back and forth freely, each of said hinge members comprising a link pivotally connected at one end to said body, a second link having one end pivotally connected to said bottom, and means for pivotally connecting said links together.
2. A golf bag including a stiff body open at the bottom, a stiff telescoping section fitted into the bottom part of said body and extending normally therefrom, hinged members connecting the bottom of said section to the bottom of said body, each of said hinge members including a pair of links, said links being pivotally connected together adjacent one end with one end of one link pivotally connected to said section and one end of the other link pivotally connected to said body, the pivotal mounting of said links being such that the links will move to a substantially radial position when said section has moved into said body and to a position substantially parallel to said body when said section has been moved substantially out of said body.

65.

3. A golf bag including a body formed with a reciprocating section at the bottom, a standard connected with said section and extending normally to near the top of said body, and an apertured plate carried by said standard, the apertures in said plate being adapted to receive golf clubs, said standard and said apertured plate reciprocating with said reciprocating section, said plate being near the top of said body when the body and said section are telescoped.

4. A golf bag provided with a body, a telescoping reciprocating section at the bottom of the bag, a standard carried by the bottom of said section, an apertured disk carried by the top of said standard, the apertures in said disk being adapted to receive golf clubs, said disk having a notch at one point, a ball pocket carried by said body positioned to extend into said notch whereby said disk may reciprocate with said section, and a cover for said balls and clubs carried by said disk, said cover extending entirely across the end of said body.

5. A golf bag including a body provided with a telescoping bottom section, a plurality of hinged members connecting the bottom of said section to the bottom of said body, each of said means including a bracket carried respectively by the body and bottom section, a lever pivotally connected with each bracket, the pivotal connection being parallel to the side walls of the body, one of said levers extending from one bracket to the other while the other lever extends for half the distance, a sleeve connected to the longer lever, and a pivotal pin for connecting the shorter lever to said sleeve at a point offset toward the bottom section whereby downward pressure on the shorter lever will act to hold the longer lever against movement, said longer lever and also the shorter lever being swung by moving the longer lever past dead center, said movement being carried out when said section is slid into said body.

6. A golf bag including a body open at the top, an open top pocket arranged interiorly of the body for receiving balls, said pocket extending longitudinally of the body, a disk arranged interiorly of said body formed with apertures for receiving and spacing golf clubs and with a notch for said pocket whereby the disk may reciprocate without interfering with the pocket, a bottom movable longitudinally of said body, a standard connected with said bottom carrying said disk, a fixed connection between said standard and said bottom, and a single covering plate for covering the open end of the body including said pocket.

FRANCIS JOHN BLATZ.
